(57) **CLAIM**

The ornamental design for a surface configuration of a gear lever for a vehicle, as shown and described.

DESCRIPTION

FIG. 1 is a perspective view of a surface configuration of a gear lever for a vehicle according to my novel design;
FIG. 2 is a rear view of the surface configuration of a gear lever for a vehicle according to my novel design;
FIG. 3 is a front view of the surface configuration of a gear lever for a vehicle according to my novel design;
FIG. 4 is a right side view of the surface configuration of a gear lever for a vehicle according to my novel design;
FIG. 5 is a left side view of the surface configuration of a gear lever for a vehicle according to my novel design;
FIG. 6 is a top view of the surface configuration of a gear lever for a vehicle according to my novel design; and,
FIG. 7 is a bottom view of the surface configuration of a gear lever for a vehicle according to my novel design.
The broken lines included depict environment and are not part of the claimed design.
